UNITED STATES PATENT OFFICE.

EDWARD W. KELLOGG, OF SCHENECTADY, NEW YORK, ASSIGNOR TO GENERAL ELECTRIC COMPANY, A CORPORATION OF NEW YORK.

RADIORECEIVING SYSTEM.

Application filed April 21, 1921. Serial No. 463,264.

To all whom it may concern:

Be it known that I, EDWARD W. KELLOGG, a citizen of the United States, residing at Schenectady, in the county of Schenectady, 5 State of New York, have invented certain new and useful Improvements in Radioreceiving Systems, of which the following is a specification.

My present invention relates to radio receiving systems, and more particularly to systems of the class in which a plurality of widely separated receiving antennæ are connected by transmission lines to a central receiving station. 10

One of the objects of my invention is to provide an improved method of operating such a system whereby an efficient reception of desired signals may be secured and the effects of disturbing influences either 15 from nearby stations or from static may be minimized. Another object of my invention is to provide an improved system of the class described whereby a more efficient reception of desired signals may be obtained. 20

In order to attain the objects of my invention I provide a plurality of receiving antennæ which are located at widely separated points, so chosen geographically that the intensity or phase relation between the signal- 25 ing impulses and disturbing influences will be different at the different points of reception. I also provide means for selectively impressing the currents received upon the receiving apparatus so that it will be possible to select for the desired reception the currents having the most favorable ratio between signal and disturbing influence. In addition I provide means for varying the phase and intensity of the currents impressed 30 upon the receiving apparatus so that by suitable adjustment the signaling currents received upon different antennæ may be brought into phase or approximate phase with one another and caused to add amplitudes in the receiving apparatus while the disturbing influences will at the same time be more or less out of phase and will combine in heterogeneous phase relation and therefore increase less rapidly than the desired signal with an increasing number of receiving antennæ. As a result the stray ratio will be greatly improved. 45

When the receiving antennæ are widely separated long transmission lines must be employed for transmitting the received sig-

naling currents to the receiving station. This involves difficulties in line construction to reduce the line losses to a minimum if the received signals are transmitted at radio frequency. To overcome this disadvantage 60 I provide detectors at each of the receiving antennæ and transmit the detected currents over the transmission lines to the central receiving station. As a result, the line construction may be greatly simplified and the 65 line losses greatly reduced. In case continuous wave signals are to be received it is desirable that the detected currents shall all be of the same frequency, and that a constant relative phase relation shall be maintained. To secure this result, I provide a single source of current at the receiving station for controlling the operation of all of the detectors and utilize the transmission lines for transmitting this current to the individual detectors. In order to eliminate the necessity of transmitting any high frequency current over the transmission lines, this source may be of comparatively low 70 frequency, and by providing frequency 75 multipliers at each receiving antennæ the frequency of the current transmitted may be multiplied to produce the high frequency current desired for the operation of the detectors. 80

The novel features which I believe to be characteristic of my invention are set forth with particularity in the appended claims; my invention itself, however, both as to its organization and method of operation will 85 best be understood by reference to the following description taken in connection with the accompanying drawing in which Fig. 1 shows diagrammatically a simple form of receiving system whereby my invention may 90 be carried into effect, and Fig. 2 illustrates a modification of the manner of transmitting the control currents from the receiving station to the individual detectors. 95

As indicated in Fig. 1, my receiving station comprises a plurality of widely separated receiving antennæ 1, 2, 3, 4, 5, connected by individual transmission lines 6, 7, 8, 9 and 10, to a central receiving station. These antennæ may be of any particular 100 type desired and their locations may be so chosen and so widely separated that the intensity and phase relations between the desired signaling currents and disturbing influences, either of static or interfering sta- 110

tions will normally be different at the different antennæ.

While all of the receiving antennæ may be located at a distance from the receiving station, it is obvious that if desired one of them, for example, antennæ 2, may be located at the receiving station. The currents received upon the separate antennæ are impressed by means of the usual coupling 5 transformers upon individual detectors 11, 12, 13, 14, 15. In order that the currents of lower than signaling frequency produced by means of all of these detectors shall have the same frequency, I provide a single source of 10 control current 16 at the receiving station. The current supplied by this source should preferably be of a frequency materially different from the frequency of the current to be produced in the detectors, but of a frequency 15 low enough to be transmitted without undue losses or restoring to special line construction. This will in general be materially below the frequency of the signaling currents to be received. The frequency 20 of the source 16 may be higher or lower than that of the detected currents to be transmitted, and in the present case I have indicated it as of higher frequency. The control current from the source 16 may be impressed 25 upon the transmission lines through condensers 17 at the receiving station and from the transmission lines upon frequency multipliers 18, 19, 20, 21 and 22 through condensers 23 at the separate receiving 30 points. These condensers should be of such value as to offer a high impedance to the low frequency signaling currents produced by the detectors whereby the efficiency 35 of transmission of these low frequency currents will be unimpaired. Choke coils 24 at the receiving station and 25 at the individual receiving points may be provided to keep the higher frequency control current from circulating in portions of the system where 40 they are not desired.

The frequency of the source 16 is so chosen that in conjunction with the frequency multipliers a current of desired frequency may be obtained for the operation 45 of detectors in order to produce therein currents which will preferably be of audio frequency for transmission to the central receiving station. The currents thus produced and transmitted over the transmission 50 lines to the receiving station may be impressed by means of intensity couplers 26 and phase rotators 27 upon the receiving apparatus which may be of any type desired. I have indicated it in the present 55 case merely by a rectangle 28.

Any convenient means, such, for example, as switches 29, 30, 31, 32 and 33 may be employed for selectively impressing upon the receiving apparatus signaling currents received 60 upon any one or more of the antennæ.

By varying the adjustment of the phase rotators and intensity couplers the desired signaling currents received upon any two or more of the antennæ may be brought into phase or approximate phase with one another so as to add amplitudes in the receiving apparatus, while the currents due to disturbing influences which are in some cases local, and in other cases general but come from miscellaneous directions will combine in heterogeneous phase relations, and will merely oppose energies.

The apparatus indicated may be utilized for receiving in a large variety of ways. It may be found that currents received upon 80 one of the antennæ have a much more favorable stray ratio than the currents received upon any of the other antennæ, in which case the current having the most favorable stray ratio may be selected for the desired 85 reception, and this current alone impressed upon the receiving apparatus.

By selectively combining the currents from two or more different antennæ in different ways and with varying phase and 90 intensity adjustments, a combination may be obtained which gives the most favorable stray ratio and this particular combination may then be utilized for the desired reception. By means of the apparatus indicated 95 the individual antenna or combination of antennæ employed for reception may be varied at will to meet varying disturbing conditions, such for example as disturbances produced by thunderstorms travelling 100 across the country in such a way that at one time one of the receiving antennæ is most seriously affected while a little later one of the other antennæ is affected to a greater extent.

In Fig. 2 I have shown a modification of my invention which may be employed where the current for controlling the operation of the detectors is too near the frequency of the signaling current to be transmitted from 110 the detectors to the receiving station to be conveniently separated therefrom by the arrangement of detectors and choke coils indicated in Fig. 1. A balanced circuit is provided in this case by means of artificial 115 lines 34 and 35 or circuits having approximately the same impedance as the transmission line so that current from the source 16 will produce no effect in the intensity coupler 26 and the beat current produced 120 by the detector 11 will not be supplied to the frequency multiplier 18.

While I have indicated and described the preferred embodiments of my invention, it will be apparent that my invention is by no 125 means limited to the particular embodiments shown and described, but that many modifications in the arrangement and connections and method of operating the apparatus may be made without departing from the scope 130

of my invention as set forth in the appended claims.

What I claim as new and desire to secure by Letters Patent of the United States is:

- 5 1. The method of operating a radio receiving system comprising a plurality of widely separated receiving antennæ and local detectors connected by transmission lines to a central receiving station which consists in transmitting over the transmission lines from the central receiving station currents of a frequency materially lower than that of the signaling waves to be received, multiplying the frequency of the currents 10 thus transmitted over the transmission lines from the central receiving station which consists in transmitting over the transmission lines from the central receiving station currents of a frequency materially lower than that of the signaling waves to be received, multiplying the frequency of the currents 15 thus transmitted at each receiving antenna to produce a current of a frequency slightly different from that of the signaling waves to be received, utilizing the currents thus produced for the operation of the detectors and thereby producing audio frequency currents and transmitting the audio frequency currents thus produced to the receiving station.
2. The method of operating a radio receiving system comprising a plurality of widely separated receiving antennæ and local detectors connected by transmission lines to a central receiving station which consists in transmitting over the transmission lines from the central receiving station currents of a frequency materially lower than that of the signaling waves to be received, multiplying the frequency of the currents 20 thus transmitted at each receiving antenna to produce a current of a frequency slightly different from that of the signaling waves to be received, utilizing the currents thus produced for the operation of the detectors and thereby producing audio frequency currents and transmitting the audio frequency currents thus produced to the receiving station.
3. The method of operating a radio receiving system comprising a plurality of widely separated receiving antennæ and local detectors connected by transmission lines to a central receiving station which consists in transmitting over the transmission lines from the central receiving station currents of a frequency materially lower than that of the signaling waves to be received, multiplying the frequency of the currents 25 thus transmitted at each receiving antenna to produce a current of a frequency slightly different from that of the signaling waves to be received, utilizing the currents thus produced for the operation of the detectors and thereby producing audio frequency currents of a frequency materially lower than that of the currents transmitted from the receiving station, and transmitting the audio frequency currents thus produced to the receiving station.
4. The method of operating a radio receiving system comprising a plurality of widely separated receiving antennæ and local detectors connected by transmission lines to a central receiving station which consists in transmitting over the transmission lines from the central receiving station currents of a frequency materially lower than that of the signaling waves to be received, multiplying the frequency of the currents 30 thus transmitted at each receiving antenna, utilizing the currents thus produced for the operation of the detectors and thereby producing audio frequency currents of a frequency materially lower than that of the currents transmitted from the receiving station and transmitting the currents of different frequency thus produced to the receiving station.
5. The method of operating a radio receiving system comprising a plurality of widely separated receiving antennæ and local detectors connected by transmission lines to a central receiving station which consists in transmitting over the transmission lines from the central receiving station currents of a frequency materially lower than that of the signaling waves to be received, multiplying the frequency of the currents 35 thus transmitted at each receiving antenna, utilizing the currents thus produced for the operation of the detectors and thereby producing currents of a frequency materially different from that of the currents transmitted from the receiving station and transmitting the currents of different frequency thus produced to the receiving station.
6. The combination in a radio receiving system of a plurality of widely separated receiving antennæ, receiving apparatus located at a central receiving station, transmission lines connecting each of said receiving antennæ with the receiving station, a detector associated with each of said antennæ, a source of control current at the receiving station of materially lower frequency than that of the signaling waves to be received, means for impressing the control current upon the transmission lines, 40 means at each antenna for multiplying the frequency of the current transmitted over the transmission lines, means for impressing the current of multiplied frequency upon the detectors to produce audio frequency currents therein and means for impressing the audio frequency currents thus produced upon the transmission lines.
7. The combination in a radio receiving system of a plurality of widely separated receiving antennæ, receiving apparatus located at a central receiving station, transmission lines connecting each of said receiving antennæ with the receiving station, a detector associated with each of said antennæ, a source of control current at the receiving station of materially lower frequency than that of the signaling waves to be received, means for impressing the control current upon the transmission lines, means at each antenna for multiplying the frequency of the current transmitted over the transmission lines, means for impressing the current of multiplied frequency upon the detectors to produce audio frequency currents therein and means for impressing the audio frequency currents thus produced upon the transmission lines.
8. The combination in a radio receiving system of a plurality of widely separated receiving antennæ, receiving apparatus located at a central receiving station, transmission lines connecting each of said receiving antennæ with the receiving station, a detector associated with each of said antennæ, a source of control current at the receiving station of materially lower frequency than that of the signaling waves to be received, means for impressing the control current upon the transmission lines, means at each antenna for multiplying the frequency of the current transmitted over the transmission lines, means for impressing the current of multiplied frequency upon the detectors to produce audio frequency currents therein and means for impressing the audio frequency currents thus produced upon the transmission lines.

4

tiplying the frequency of the current transmitted over the transmission lines, means for impressing the current of multiplied frequency upon the detectors to produce audio 5 frequency currents therein, of a frequency materially lower than that of the currents transmitted from the receiving station; and means for impressing the audio frequency currents thus produced upon the transmission lines.

8. The combination in a radio receiving system of a plurality of widely separated receiving antennæ, receiving apparatus located at a central receiving station, transmission lines connecting each of said receiving antennæ with the receiving station, a detector associated with each of said antennæ, a source of control current at the receiving station of materially lower frequency than that of the 15 signaling waves to be received, means for impressing the control current upon the transmission lines, means at each antenna for multiplying the frequency of the current transmitted over the transmission lines to 20 produce a current of a frequency slightly different from that of the signaling waves to be received, means for impressing the current of multiplied frequency upon the detectors to produce audio frequency currents therein, and means for impressing the audio frequency currents thus produced upon the 25 transmission lines.

9. The combination in a radio receiving system of a plurality of widely separated receiving antennæ, receiving apparatus located at a central receiving station, transmission lines connecting each of said receiving antennæ with the receiving station, a detector associated with each of said antennæ, a source 30

of control current at the receiving station of 40 materially lower frequency than that of the signaling waves to be received, means for impressing the control current upon the transmission lines means for each antenna for multiplying the frequency of the current transmitted over the transmission lines, means for impressing the current of multiplied frequency upon the detectors to produce currents therein, of a frequency materially lower than that of the currents transmitted from 45 the receiving station, and means for impressing the currents thus produced upon the transmission lines.

10. The combination in a radio receiving system of a plurality of widely separated 50 receiving antennæ, receiving apparatus located at a central receiving station, transmission lines connecting each of said receiving antennæ with the receiving station, a detector associated with each of said antennæ, a 55 source of control current at the receiving station of materially lower frequency than that of the signaling waves to be received, means for impressing the control current upon the transmission lines, means at each antenna 60 for multiplying the frequency of the currents transmitted over the transmission lines, means for impressing the current of multiplied frequency upon the detectors to produce currents therein of a frequency different 65 from that of the currents transmitted from the receiving station, and means for impressing the currents thus produced upon the transmission lines.

In witness whereof I have hereunto set my 70 hand this 20th day of April 1921.

EDWARD W. KELLOGG.
